X-RAY GENERATOR AND X-RAY ANALYZER

TECHNICAL FIELD

The present invention relates to an X-ray generator having as anode that is equipped with a plurality of X-ray generation zones. The invention also relates to an X-ray analyzer that employs the X-ray generator.

BACKGROUND ART

In X-ray analyzers, i.e., X-ray diffractometers, fluorescent X-ray devices, small-angle X-ray scattering devices, and the like, X-rays generated from an X-ray generator irradiate a specimen targeted for analysis. In a typical X-ray generator, electrons generated from a cathode are made to collide against the surface of an anode, thereby generating X-rays from the surface of the anode. The region where the electrons collide, i.e., the region where X-rays are generated, is typically called the X-ray focal point.

The wavelength of the X-rays generated from the anode is determined by the material of the region that corresponds to the X-ray focal point in the anode. Known materials for anodes include Cu (copper), Mo (molybdenum), Cr (chromium), Co (cobalt), and the like. The material of the anode, is selected, as appropriate, according to the type of analysis that is to be carried out. For example, in a case in which structural analysis of a protein is to be carried out by an X-ray diffractometer, a plurality of materials selected from the above plurality of mate would be employed.

Conventionally, according to Patent Literature 1, there is disclosed in FIG. 1 of the Literature a configuration for using negative pressure produced by suction of air to move the anode housing that supports the anode, and by this movement selectively arranging an X-ray generation -zone of one kind from among two kinds on the anode, to a position facing the cathode.

In this conventional device, a gap is formed by means of two wall surfaces, namely, a wall surface of a casing that houses the anode and a wall surface of a protruding member that extends from the casing, and within this gap is arranged a flange that extends from the anode housing. The components are then arranged so that the cathode and one of the X-ray generation zones are facing when the flange of the anode housing has abutted the wall surfaces, and the cathode and another one of the X-ray generation zones are facing when the flange of the anode housing has abutted the wall surface of the protruding member.

That is, in the X-ray generator of Patent Literature 1, two X-ray generation zones are respectively arranged at positions facing the cathode, while using the wall surface of the casing and the wall surface of protruding member as stoppers. However, with this method, there is a problem in that for an anode equipped with three or more X-ray generation zones, any one of the X-ray generation zones thereof cannot be stationed at a position facing the cathode.

According to FIG. 8 of Patent Literature 1, there is disclosed a method whereby a stopper device for an anode equipped with three or more X-ray generation zones is configured by placing the distal end of a check bolt in abutment against a flange of the housing to station any one of the X-ray generation zones at a position facing the cathode. With this method, the amount of threading of the

check bolt is adjusted to change the position of the distal end, so that the position at which the anode stops can be changed.

CITATION LIST

Patent Literature

Patent Literature 1: Japanese Unexamined Patent Application Publication No. 2008-269933

SUMMARY OF INVENTION

Technical Problem

However in the position adjustment method for the anode X-ray generation zones disclosed in Patent Literature 1, the check screw is threaded in manually, and therefore there was a problem in that it is not possible to automate the task of selecting one of a plurality of X-ray generation zones and arranging the zone at a position facing the cathode, and the process cannot be carried out with high accuracy.

The present invention was contrived in view of the aforementioned problems of the prior art devices, and has as an object to provide an X-ray generator and an X-ray analyzer with which one of three or more X-ray generation zones provided on an anode can be stationed at a prescribed position facing the cathode, and by which the operation can be carried out automatically and with high accuracy.

Solution to Problem

The X-ray generator according to the present invention is an X-ray generator comprising: a cathode for generating electrons; an anode provided facing the cathode, and equipped with a plurality of X-ray generation zones which are lined up adjacently to one another; a casing fox housing the cathode and the anode in the interior thereof, and integrated with the cathode; an anode support body for supporting the anode; driving means for driving the anode support body in such a way that the anode support body and the casing undergo relative advancing and retreating movement; and stopper means for stopping motion of the anode support body when the anode support body and the casing move in a direction of approaching one another. The stopper means comprising: a mobile platform equipped with a section that enters and exits from between the anode support body and the casing; a mobile platform drive means for driving the mobile platform; and a plurality of stop members of mutually different heights provided in the entering and exiting section of the mobile platform.

According to this X-ray generator, the plurality of stop members of different heights are moved by a mobile platform drive means such as a motor, whereby the positions of a plurality of X-ray generation zones of the anode are changed, and therefore setting of the position of the X-ray generation zones can be accomplished automatically rather than manually.

Further, conventionally, the distal end surface of a check bolt was employed as a stopper in order to adjust the positions of three or more X-ray generation zones, and the position of the distal end of the check bolt was changed by varying the amount of threading of the check bolt. With this method, the position of the X-ray generation zones could not be adjusted finely or with high accuracy.

By contrast, according to the present embodiment, any one of the plurality of stop members of different heights is

selectively interposed between the anode support body and the casing, whereby the anode which is supported by the anode support body and the cathode which is supported by the casing are adjusted in their relative positions, and therefore the relative positions of the cathode and the X-ray generation zones on the anode can be positioned finely and with high accuracy.

the X-ray generator according to the present invention, the mobile platform may be provided in such a way as to be able to move in a direction closer towards or away from the casing, in a state in which at least one of the plurality of stop members is placed between the anode support body and the casing. With this configuration, unwanted load bearing on the mobile platform which supports the stop members can be prevented.

In the aforementioned configuration, the stop members may be urged by elastic members (e.g., compression springs). With this configuration, the stop members which are moveably provided on the mobile platform can be kept always arranged at a given position in a natural state by means of the elastic force of the elastic members.

In the aforementioned configuration, the stop members may have lengths that are greater than the thickness of the mobile platform, the stop members may be provided to pass through the mobile platform, and the stop members may be configured such that one end thereof is capable of abutting against either the casing or the anode support body, and the other end of the stop member is capable of abutting against the other of the casing or the anode support body.

In the X-ray generator of the present invention, the mobile platform may be a rotating plate, the plurality of entering and exiting sections may peripheral sections of the rotating plate, and the plurality of stop members may be provided at different positions of the peripheral sections of the rotating plate. With this configuration, the stopper means of the present invention can be this configuration, the stopper means of the present invention can be realized in a simple fashion.

In the aforementioned X-ray generator having a rotating plate as the mobile platform, the mobile platform moving means can be a motor, the motor may be one having a main body section, and an output shaft that extends to the outside from the interior of the main body section, the rotating plate may be attached to the output shaft, and the main body section of the motor may be secured to the anode support body or to the casing.

In the X-ray generator of the present invention, a plurality of the stopper means may be provided on the anode support body or on the casing. In so doing, positioning of the anode can be carried out with high accuracy.

The X-ray generator of the present invention employing the plurality of stopper means may have a seal member for airtightly partitioning a space between the anode support body and the casing. In this X-ray generator, the plurality of stopper means may be arranged point-symmetrically with respect to the center axis of the seal member within a plane orthogonal to the center axis, or line-symmetrically with respect to a line that passes through the center axis. In so doing, the accuracy of positioning of the anode can be further enhanced.

In the X-ray generator of the present invention which employs a plurality of the stopper means, the stopper means may be arranged at mutually equidistant spacing with respect to the center axis of the seal member, and at mutually equiangular spacing about the center axis. In so doing, the accuracy of positioning of the anode can be further enhanced.

In the X-ray generator of the present invention, the space between the anode support body and the casing may be airtightly partitioned by a bellows. That is, the seal member may be formed by the bellows. The stopper means may be provided outside the bellows. With this configuration, the X-ray generator can be easily manufactured.

In the X-ray generator according to the present invention, the anode support body may have an anode housing that supports the anode and extends to the outside of the anode, and a support plate that is secured to the anode housing and extends in a direction traversing the direction of extension of the anode housing. The drive means and the stopper means may be arranged on the support plate. With this configuration, a structure for supporting the anode can be formed in a simple manner, and the X-ray generator, including the drive means and the stopper means, can be kept compact.

Next, the X-ray analyzer of the present invention is an X-ray analyzer comprising an X-ray generator of the configuration disclosed above, and an X-ray optical system employing X-rays generated by the X-ray generator. The X-ray optical system may be, for example, an optical system comprising a combination of a divergence slit, scattering slit, receiving slit, an X-ray detector 13, and the like. Elements besides these X-ray optical elements may be included in the X-ray optical system as well.

Advantageous Effects of Invention

According to the X-ray generator of the present invention, the plurality of stop members of different heights are moved by the mobile platform moving means, which is a motor or the like, whereby one of the plurality of stop members can be selected, for use. As a result, positioning of the X-ray generation zones can be carried out automatically, not manually.

Moreover, conventionally, the distal end surface of a check bolt was employed as a stopper in order to adjust the positions of three or more X-ray generation zones, and the position of the distal end surface of the check bolt was changed by varying the amount of threading of the check bolt. With this method, the position of the X-ray generation zones could not be adjusted automatically/with high accuracy.

By contrast, according to the X-ray generator of the present invention, any one of the plurality of stop members of different heights is interposed between the anode support body and the casing, whereby a plurality of X-ray generation zones located at a multitude of different positions on the anode can be positioned finely and with high accuracy, with respect to the cathode.

BRIEF DESCRIPTION OF DRAWINGS

FIG. 1 is a front view showing an embodiment of the X-ray analyzer according to the present invention;

FIG. 2 is a front view showing an embodiment of the X-ray generator according to the present invention, viewed along arrow A in FIG. 1;

FIG. 3 is a cross sectional view showing the longitudinal cross sectional structure of the X-ray generator, taken along line B-B in FIG. 2;

FIG. 4 is a cross sectional view showing the planar cross sectional structure of the X-ray generator, taken along line C-C in FIG. 2;

FIG. 5 is a cross sectional view, taken along line C-C in FIG. 2, showing the longitudinal cross sectional structure of an assist unit which is a principal part of the X-ray generator;

FIG. 6 is a cross sectional view, taken along line K-K in FIG. 2, showing the longitudinal cross sectional structure of a stopper device which is another principal, part of the X-ray generator;

FIG. 7 is a plan view showing the planar structure of the stopper device, taken along line M-M in FIG. 6;

FIG. 8 is a side view of the stopper device taken along line N-N in FIG. 7;

FIG. 9 is a side view showing the stopper device shown in FIG. 8, depicted while performing a stopper function; and

FIG. 10 is a cross sectional view showing another embodiment of the X-ray analyzer according to the present invention.

DESCRIPTION OF EMBODIMENTS

The X-ray generator and the X-ray analyzer according to the present invention shall be described below on the basis of embodiments. The present invention is not limited to these embodiments, as shall be apparent. In the drawings appended to the present description, constituent elements are in some instances depicted at a scale different from the actual one, in order to facilitate understanding of characteristic features.

(X-Ray Diffractometer)

FIG. 1 is a front view showing an X-ray diffractometer 1 as an embodiment of the X-ray analyzer according to the present invention. The in-plane direction of the page in the drawing is the vertical direction, and the direction passing through the page is the horizontal direction. This X-ray diffractometer 1 has an X-ray generator 2 and a goniometer 3. The goniometer 3 has a θ -rotation platform 4, a 2θ -rotation platform 5, and a detector arm 6 that extends from the 2θ -rotation platform 5.

The θ -rotation platform 4 is rotatable about its own center axis ω . The center axis ω extends in a direction passing through the page on FIG. 1. The 2θ -rotation platform 5 is also rotatable about this same center axis ω . A divergence slit 7 is provided between the X-ray generator 2 and the goniometer 3. This divergence slit 7 regulates divergence of X-rays exiting from the X-ray generator 2, and causes the X-rays to irradiate a specimen S.

A specimen holder 10 is detachably installed on the θ -rotation platform 4, and the specimen S being measured is accommodated within the specimen holder 10. For example, the specimen S may be packed into a recessed portion or through-opening provided to the specimen holder 10. On the detector arm 6 are provided a scattering slit 11, a receiving slit 12, and a two-dimensional X-ray detector 13 by way of an X-ray detection means. The scattering slit 11 prevents scattered rays which are unwanted for the purposes of analysis from entering the X-ray detector 13. The receiving slit 12 passes secondary X-rays, e.g., diffracted X-rays, exiting from the specimen S, while blocking other unwanted X-rays.

The two-dimensional X-ray detector 13 has a two-dimensional sensor 14. The two-dimensional sensor 14 is an X-ray sensor that has a position resolution function in a two-dimensional area (i.e., within a plane). A position resolution function is a function for detecting X-ray intensity on a per-position basis. This two-dimensional sensor 14 is an X-ray detector having, for example, a plurality of photon-counting type pixels arranged two-dimensionally (i.e., in planar fashion). The sensor has the function of outputting electrical signals of magnitude that corresponds to the intensity of X-rays received by the individual photon-counting type pixels. Therefore, the two-dimensional sensor 14 is

designed to simultaneously receive in planar fashion X-rays from a plurality of pixels, and independently output electrical signals from each of the pixels.

The two-dimensional sensor 14 could also be configured from a two-dimensional charge coupled device (CCD) sensor. A two-dimensional CCD sensor is a two-dimensional sensor in which individual pixels for receiving X-rays are formed by CCDs.

Depending on the type of measurement being performed, 10 a one-dimensional X-ray detector could be used in place of the two-dimensional X-ray detector 13. A one-dimensional X-ray detector is an X-ray detector that has a position resolution function within a one-dimensional area (i.e., within a linear area). The one-dimensional X-ray detector 15 may be, for example, a position sensitive proportional counter (PSPC), an X-ray detector that employs a one-dimensional CCD sensor an X-ray detector in which a plurality of photon-counting type pixels are arranged one-dimensionally, or the like.

20 Depending on the type of measurement being performed, a 0(zero) dimensional X-ray detector may be used instead of a two-dimensional X-ray detector. A 0 (zero) dimensional X-ray detector is an X-ray detector that lacks a position resolution function relating to X-ray intensity. This 0 (zero) 25 dimensional X-ray detector may be, for example, an X-ray detector that employs a proportional counter (PC), an X-ray detector that employs a scintillation counter (SC), or the like.

The X-ray generator 2 is arranged secured at a given 30 position. This X-ray generator 2 has a cathode 16 that emits thermal electrons through electrical conduction, and a rotating anode 17 arranged facing the cathode 16. Electrons emitted from the cathode 16 collide at high speed with the outer peripheral surface of the rotating anode 17. The area in 35 which the electrons collide is an X-ray focal point F, and X-rays are generated at this X-ray focal point. The planar shape of the X-ray focal point is, for example, 0.2 mm $\times$ 2 mm. The X-rays R1 generated from the rotating anode 17, the divergence angle thereof having been regulated by the 40 divergence slit 7, impinge on the specimen S.

The θ -rotation platform 4 rotates about the ω -axis while 45 driven by a θ -rotation driving device 20. This rotation is intermittent rotation at prescribed step angles, or continuous rotation at a prescribed angular velocity. This rotation of the θ -rotation platform 4 is rotation that takes place in order to change the angle of incidence θ of X-rays on the specimen S, and is typically called θ -rotation.

The 2θ -rotation platform 5 rotates about the ω -axis while 50 driven by a 2θ -rotation driving device 21. This rotation is typically called 2θ -rotation. This 2θ -rotation is rotation that takes place in such a way that when secondary X-rays (e.g. diffracted X-rays) R2 are generated from the specimen S at times when X-rays, are incident on the specimen S at an incident angle θ , the secondary X-rays can be received by 55 the X-ray detector 13.

The θ -rotation driving device 20 and the 2θ -rotation driving device 21 may be configured with any rotation driving devices. Such a rotation device may be configured, for example, from a rotation power source and a power 60 transmission device. The rotation power source may be configured, for example, with a controllable-rotation speed motor, e.g., a servo motor, or a stepping motor. The power transmission device may be configured, for example, with a worm secured to the output shaft of the rotation power source, and a worm wheel that meshes with the worm, and is secured to the center shaft of the θ -rotation platform 4 or to the center shaft of the 2θ -rotation platform 5.

When the θ -rotation platform **4** and the specimen **S** installed thereon undergo θ -rotation, and the 2θ -rotation platform **5** and the X-ray detector **13** supported thereon undergo 2θ -rotation, the X-ray focal point **F** is arranged fixed on a goniometer circle **Cg** that is centered on the axis ω , while the X-ray collection point of the receiving slit **12** moves over the goniometer circle **Cg**. During θ -rotation of the specimen **S** and 2θ -rotation of the X-ray detector **13**, the X-ray focal point **F**, the ω -axis, and the X-ray collection point of the receiving slit **12** are present on a focusing circle **Cf**. The goniometer circle **Cg** is a constant-radius hypothetical circle, and the focusing circle **Cf** is a hypothetical circle that changes in radius in association with changes of the θ angle and the 2θ angle.

In the present embodiment, the X-ray optical system is configured with the divergence slit **7**, the specimen **S**, the scattering slit **11**, the receiving slit **12**, and the X-ray detector **13**. If needed, the X-ray optical system may include other X-ray optical elements. Such X-ray optical elements could be, for example, a collimator, a solar slit, a monochromator, or the like.

The operation of the X-ray diffractometer **1** configured as described above will be described below.

First, if needed, the various X-ray optical elements present on the X-ray path leading from the X-ray focal point **F** to the X-ray detector **13** are correctly aligned in position on the X-ray optical axis. That is, optical axis adjustment is performed. Next, the X-ray incident angle θ with respect to the specimen **S** and the diffraction angle 2θ of the X-ray detector **13** are set so the desired initial positions (zero positions).

Next, by passing current through the cathode **16** to heat it, thermal, electrons are generated from the cathode **16**. These electrons, while being restricted in the direction of advance by an electric field that is usually applied by a Wehnelt (not illustrated), collide at high speed against the surface of the rotating anode **17** and form the X-ray focal point **F**. X-rays of wavelength that is dependent on the material of the rotating anode **17** are then emitted from the X-ray focal point **F**. The current that flows to the rotating anode **17** from the cathode **16** due to electrical conduction to the cathode **16** is typically called tube current. In order to accelerate the electrons that are emitted from the cathode **16** and collide with the rotating anode **17**, a prescribed large voltage is applied across the cathode **16** and the rotating anode **17**. This voltage is typically called tube voltage. In the present embodiment, the tube voltage and the tube current are respectively set to 30-60 kV and 10-120 mA. The rotating anode material will be discussed below.

The X-rays **R1** that are emitted and diverge from the X-ray generator **2** include continuous X-rays that include X-rays of various wavelengths, and characteristic X-rays of specific wavelength. In cases in which it is desired to select desired characteristic X-rays from among these X-rays, an incidence-side monochromator (an "incident monochromator") is provided on the X-ray optical path leading from the X-ray generator **2** to the specimen **S**. The X-rays **R1**, divergence of which is regulated by the divergence slit **7**, irradiate the specimen **S**. During intervals in which the specimen is undergoing θ -rotation and the X-ray detector **13** is undergoing 2θ -rotation, when the X-rays **R1** incident on the specimen **S** meet a prescribed rotation condition, with respect to the crystal, lattice planes inside the specimen, specifically, an angular state that satisfies the Bragg's diffraction angle, secondary X-rays, e.g., diffracted rays **R2**, are generated at a diffraction angle of 2θ from the specimen **S**. These diffracted rays **R2** pass through the scattering slit **11**

and the receiving slit **12** to be scattering slit **11** and the receiving slit **12** to be received by the X-ray detector **13**. The X-ray detector **13** outputs a signal that is dependent on the count of X-rays received at individual pixels of the X-ray detector **13**, and X-ray intensity is calculated on the basis of this output signal.

The aforescribed X-ray intensity calculation process is carried out on each angle among the incident X-ray angles θ and the diffraction angles 2θ , as a result of which there is derived an X-ray intensity $I(2\theta)$ at each angular position of the diffraction angle 2θ . By plotting the X-ray intensity $I(2\theta)$ on plane coordinates where the diffraction angle 2θ is the horizontal axis and the X-ray intensity I is the vertical axis, an X-ray diffraction diagram of known type is derived. By then observing the generated, intensity (I) and the angle (2θ) at which the X-ray intensity peak waveform appearing on the X-ray diffraction diagram is generated, the internal structure of the specimen **S** can be analyzed.

(X-ray Generator)

The X-ray generator **2** will be described in detail below.

FIG. 2 shows the X-ray generator **2** viewed along arrow **A** in FIG. 1. FIG. 3 shows the longitudinal cross sectional structure of the X-ray generator **2**, taken along line **B-B** in FIG. 2. FIG. 4 shows the planar cross sectional structure of the X-ray generator, taken along line **C-C** in FIG. 2. In FIG. 2 and FIG. 4, the X-ray generator **2** has the cathode **16** mentioned previously, the rotating anode **17** mentioned previously, an anode unit **24** that includes the rotating anode **17**, and a bellows **36**, as a seal material.

In the present embodiment, a welded bellows is employed as the bellows **36**. The welded bellows has an accordion shape in which the outer peripheries and inner peripheries of a plurality of thin ring-shaped metal plates are joined together by welding. The bellows **36** is round in shape when viewed in the direction of arrow **A**, and cylindrical in shape overall. On the outer peripheral surface of the rotating anode **17** are provided a plurality (in the present embodiment, five) X-ray generation zones **21A**, **27B**, **27C**, **27D**, **27E**, which are lined up adjacently to one another. The center axis **X1** of the cylindrical shape of the bellows **36** extends in the direction in which the X-ray generation zones **27A** to **27E** are lined up (the vertical direction in FIG. 4).

One end of the bellows **36** (e.g., the end at the top side in FIG. 4) is anchored to a first flange **36a**, by welding for example. The other end of the bellows **36** (the end at the bottom in FIG. 4) is anchored to a second flange **36b**, by welding for example. As shown in FIG. 2, the planar shape of the first flange **36a** is round.

For the planar shape and thickness of the first flange **36a** and the second flange **36b**, there can be adopted any shape besides the illustrated shapes, as needed. In some instances, the bellows **36** can be formed by a molded bellows instead of a welded bellows, or by a bellows of some other configuration. Molded bellows are bellows that have been formed by a molding process, instead of welding.

In FIG. 3 and FIG. 4, the first flange **36a** of the bellows **36** is anchored by a bolt or other fastening means to a base **29** which is a metal member. An O-ring (i.e., an elastic ring) **23** for maintaining airtightness is interposed between the base **29** and the first flange **36a**. A casing **25** is formed by the base **29** and the first flange **36a**. The casing **25** has an internal space **H** for accommodating the anode **17** and the cathode **16**. The base **29** (and hence the casing **25**) and the cathode **16** are integrated.

An X-ray window **28** for extraction of the X-rays **R1** generated by the rotating anode **17** is provided in a section

of the base 29 of the casing 25. The X-ray window 28 is formed from a material through which X-rays can pass, for example, beryllium (Be).

The rotating anode unit 24 has an anode housing 26 that supports the rotating anode 17 and extends to the outside of the rotating anode 17. The anode housing 26 rotatably supports the rotating anode 17 about the axis X0 as shown by arrow D. The base 29 and the anode housing 26 are formed, for example, from copper or copper alloy. The anode housing 26 is formed to cylindrical shape as viewed from the direction of arrow A. The base 29 is formed to cylindrical shape as viewed from the direction of arrow A. The base 29 may be a cornered tube shape as well.

The rotating anode 17 is formed by disposing in a row arrangement a plurality of types (in the present embodiment, five types) of X-ray generation cones 27A, 27B, 27C, 27D, 27E on the outer peripheral surface of a base member formed from a material having high thermal conductivity (e.g., copper (Cu) or a copper alloy). The rotating anode 17 has a cup shape whose top is a closed plane as shown in FIG. 4. The X-ray generation zones 27A, 27B, 27C, 27D, 27E are lined up in the direction of extension of the center axis X0 of the rotating anode 17 (i.e., the axial direction of the rotating anode unit 24) and provided in ring shape (i.e. annular shape) in a band shape. The X-ray generation zones 27A, 27B, 27C, 27D, 27E are formed from mutually different materials, each being one material selected, e.g., from among Cu, Mo (molybdenum), Cr (chromium), Co (cobalt), or other metals.

The materials Mo, Cr, and Co are formed on a Cu base member, for example, by ion plating, plating, shrink fitting, or other appropriate film, forming method. The widths of the X-ray generation zones 27A, 27B, 27C, 27D, 27E in the axial direction are set to mutually equal lengths. Specifically, where the dimensions of the X-ray focal spot F are 0.2 mm×2 mm, the widths of the X-ray generation zones 27A, 27B, 27C, 27D, 27E in the axial direction are set to about 3 mm.

The anode housing 26 is formed to generally cylindrical shape centered on the axis X0. As shown in FIG. 3, in the interior of the anode housing 26 are provided a rotating shaft 30 which is integrated with the rotating anode 17, a motor 40 serving as the rotation driving device for driving rotation of the rotating shaft 30, a magnetic seal device 38 provided around the rotating shaft 30, and a water passage 31 for water used to cool the rotating anode 17. The rotating anode 17 rotates upon being driven by the motor 40. The rotation speed of the rotating anode 17 is 6,000 rpm, for example.

The magnetic seal device 38 is a shaft seal device for maintaining a pressure differential between the internal space H of the casing 25, which is in a high vacuum state, and the internal space of the anode housing 26, which communicates with atmospheric pressure. The magnetic seal device 38 has a magnetic fluid deposited on the outer peripheral surface of the rotating shaft 30 by magnetic force. Due to this magnetic fluid, a high vacuum is maintained to one side of the magnetic seal device 38, and atmospheric pressure to the other side. Because the magnetic fluid does not exert significant torque on the rotating shaft 30, the magnetic seal device 38 does not hamper rotation of the rotating shaft 30.

The water passage 31 connects to a water supply port 46 and a water discharge port 47 which are provided at the back end of the anode housing 26 (the left end in FIG. 3). Cooling water introduced into the anode housing 26 from the water supply port 46 is fed to the interior of the rotating anode 17 through the outbound section of the water passage 31, and

cools the rotating anode 17 from the inside, and thereafter passes through the return section of the water passage 31 and is discharged to the outside from the water discharge port 47.

The internal structure of the rotating anode unit 24 is generally as described above. More specifically, the internal structure of the rotating anode unit disclosed, for example, in Japanese Unexamined Patent Application Publication 2008-269933 can be adopted.

In FIG. 3 and FIG. 4, the second flange 36b of the bellows 36 is secured to a flange 35 which is provided to the anode housing 26. The bellows 36 keeps the internal space K of the casing 25 in an airtight state with respect to atmospheric pressure. As shown in FIG. 4, this internal space H connects to an exhaust device 34. The exhaust device 34 evacuates air from within this internal space H and maintains a high vacuum (hereinafter simply termed a "vacuum state") in the internal space H.

The exhaust device 34 can be configured, for example, as a combination of a rotary pump and a turbo molecular pump. The rotary pump is a pump that can reduce the pressure in the internal space H to a low vacuum. The turbo molecular pump is a pump that can further evacuate to a high vacuum state the atmosphere that has been reduced in pressure by the rotary pump. Through the action of this turbo molecular pump, the surrounding area of the rotating anode 17 and the cathode 16 can be placed under a high vacuum of 10^{-3} Pa or lower. Provided that the interior of the casing 25 can be placed in a high vacuum state, a combination of a high vacuum pump other than a turbo molecular pump and an auxiliary pump other than a rotary pump can be adopted.

In the present embodiment, the casing 25 is secured at an appropriate location of the X-ray diffractometer 1 of FIG. 1. In FIG. 4, the bellows 36 is a member which is extendable along its own center axis X1. In the present embodiment, the center rotational axis X0 of the rotating anode 17 diverges from the center axis X1 of the bellows 36. Naturally, the center rotational axis X0 of the anode housing 26 may be aligned with the center axis X1 of the bellows 36.

By disposing the bellows 36 between the casing 25 and the anode housing 26 in FIG. 4, even if the second flange 36b undergoes advancing or retracting motion with respect to the casing 25, the internal space H surrounding the anode 17 can be maintained in an airtight state by the extending and contracting action of the bellows 36. In the present embodiment, the anode housing 26 and the second flange 36b constitute an anode support body 32 for supporting the anode 17.

In FIG. 2, the surface 36c of the second flange 36b on the side away from the anode 17 (the front side in FIG. 2) is provided with a plurality (in the present embodiment, two) of air cylinders 41a, 41b as driving means, a plurality (in the present embodiment, two) of linear guides 42a, 42b as guiding means, a plurality (in the present embodiment, four) of assist units 43a, 43b, 43c, 43d as elastic force imparting means, and a plurality (in the present embodiment, four) of stopper devices 44a, 44b, 44c, 44d as stopper means. In this manner, the second flange 36b of the bellows 36 functions as a support plate for supporting these devices, i.e., the air cylinders 41, 41b, the linear guides 42a, 42b, the assist units 43a, 43b, 43c, 43d, and the stopper devices 44a, 44b, 44c, 44d. Hereinafter, the second flange 36b is sometimes referred to as a support flange 36b.

In FIG. 4, the linear guide 42a, 42b have dovetail tail units 55 and dovetail groove units 56. The dovetail tail units 55 have a support column 57a secured to the surface 36c of the support plate 36b, and a dovetail tail 58 serving as a guided member and provided on a side surface of the support

column 57a. The support column 57a and the dovetail tail 58 extend in the direction of the center axis X1 of the bellows 36. The dovetail groove units 56 have a support column 57b secured to the first flange 36a constituting the casing 25, and a dovetail groove member 59 serving as a guide member and provided on a side surface of the support column 57b. The support column 57b and the dovetail groove member 59 serving as a guide in the direction of the center axis Z1 of the bellows 36.

The dovetail tails 58 mate with the dovetail grooves of the dovetail groove members 59. The mating of the dovetail tails and the dovetail grooves involves mating in such a way that the parts are slideable in the lengthwise direction (i.e., capable of sliding movement), but are not able to release from the mated state in directions perpendicular to the lengthwise direction. The anode support body 32 which supports the anode 17 moves parallel to the casing 25 as shown by arrow E and arrow J while being guided by the linear guides 42a, 42b. Through this action of the linear guides 42a, 42b, the anode support body 32 is guided in such a way as to not experience lateral swaying or tilting. In so doing, the anode 17 can experience parallel movement without laterally swaying within the internal space H of the casing 25.

As shown in FIG. 3, the air cylinders 41a, 41b shown in FIG. 2 have a cylinder body 48 and an output rod 49. The cylinder body 48 is secured onto the surface 36c of the support plate 36b, on the opposite side thereof from the anode 17. The distal end of the output rod is secured to the first flange 36a, i.e., to the casing 25, by a bolt 50.

The cylinder body 48 is provided with a first air connection port 51 and a second air connection port 52. These air connection ports are connected to an air supply source, not illustrated. When air is supplied to the first air connection port 51, the output rod 49 experiences extending motion. Due to this extending motion, the support plate 36b experiences parallel motion in a direction away from the casing 25 as shown by arrow E. When air is supplied to the second air connector port 52, the output rod 49 experiences contracting motion. Due to this contracting motion, the support plate 36b experiences parallel motion in a direction towards the casing 25 as shown by arrow J. When the support plate 36b experiences parallel motion in the direction of arrow E or the direction of arrow J, the anode 17 which is integrated therewith experiences parallel motion in the same direction. Due to this parallel motion, of the anode 17, any one of the X-ray generation zones 21A, 21B, 27C, 27D, or 27E provided on the anode 17 can be selectively transported to a position facing the cathode 16.

FIG. 5 shows a cross sectional, structure of an assist unit 43a, taken in the longitudinal direction along line G-G in FIG. 2. The other assist units 43b, 43c, 43d are identical in structure. The assist unit 43a has a through-hole 62 that opens through the support plate 36b constituting the second flange of the bellows 36, a compression spring 63 that abuts at one end the first flange 36a (which constitutes the casing 25) of the bellows 36, and a spring cover 64 fitted at one end into the through-hole 62 of the support plate 36b. The compression spring 63 passes through the through-hole 62 of the support plate 36b.

An end of the spring cover 64 which is fitted into the through-hole 62 of the support plate 36b is open, and the end on the opposite side therefrom is closed. The spring cover 64 compresses the compression spring 63 by means of the closed end. The compression spring 63 imparts to the anode support body 32 spring force (i.e., elastic force) commensurate to the compressed length. In this way, the anode

support body 32 is urged in the direction of arrow E (i.e., a direction away from the internal space H) by the compression spring 63.

In FIG. 4, the internal space H of the casing 25 is evacuated and set to a vacuum state by the exhaust device 34. For this reason, the anode support body 32 which comprises the anode housing 26 and the support plate 36b tends to be pushed by atmospheric pressure pushing it in the direction of arrow J (i.e., the direction towards the internal space H). The urging force exerted in the direction of arrow E on the anode support body 32 by the compression spring 63 of FIG. 5 acts as force to push back in the opposite direction the anode support body 32 which is being vacuum suctioned, to produce a balance of force.

FIG. 6 shows the longitudinal cross-sectional structure of the stopper device 44b, taken along line K-K in FIG. 2. The other stopper devices 44a, 44c, 44d are identical in structure. In FIG. 6, the stopper device 44b has a rotating plate 68 as a mobile platform, and an electric motor 69 as mobile platform driving means. The electric motor (hereinafter simply called a "motor") 69 has a motor body 70 and an output shaft 71. The motor body 70 is secured to a surface 36c of the support plate 36b on the opposite side from the internal space H. The output shaft 71 passes through a through-hole 72 provided to the support plate 36b on the opposite side from opposite side of the support plate 36b. The rotating plate 68 is secured to the output shaft 71 jutting toward the opposite side of the support plate 36b. The motor 69 is a motor in which the rotation angle of the output shaft 71 is controllable, e.g., a servo motor or a pulse motor. The rotating plate 68 is driven by the motor 69 and rotates about the output shaft 71 as indicated by arrow L.

FIG. 7 shows the planar configuration of the stopper device 44b, taken along line M-M in FIG. 6. As shown in FIG. 7, the rotating plate 68 attached to the output shaft 71 of the motor 69 is formed to a round shape. When the motor 69 operates and the output shaft 71 rotates, the rotating plate 68 rotates as shown by arrow L. There are also instances of rotation in the opposite direction of arrow L. When the rotating plate 68 rotates in this manner, an annular peripheral section of the rotating plate 68 goes into and out from a region R sandwiched by the casing 25 and the support plate 36b which supports the motor 69.

The annular peripheral section of the rotating plate 68 (i.e., the section that enters and exits from between the casing 25 and the support plate 36b) is provided with a plurality of stop members 73a, 73b, 73c, 73d, 73e. In the present embodiment, the stop members number five. FIG. 8 shows the structure of a side surface of the stop member 44b, taken along line N-N in FIG. 7. As shown in FIG. 8, each of the five stop members 73a, 73b, 73c, 73d, 73e in a shaft portion thereof passes through a through hole provided to the rotating plate 68. The shaft members are capable of sliding in the axial direction in the axial direction relative to the rotating plate 68.

Retaining rings 74 are attached at the distal ends (top ends in FIG. 8) of the shaft portions of the stop members 73a, 73b, 73c, 73d, 73e. Compression springs 75 are provided between the rotating plate 86 and the heads of the stop members 73a, 73b, 73c, 73d, 73e. Through this configuration, in the natural state, the stop members 73a, 73b, 73c, 73d, 73e are urged in a direction shown by arrow J (i.e., towards the anode 17 (see FIG. 6)) by the spring force (i.e. elastic force) of the compression springs 75.

13

The heights P1, P2, P3, P4, P5 of the stop members 73a, 73b, 73c, 73d, 73e, as measured from the surface on the casing 25 side of the rotating plate 68, differ from one another.

Specifically,

$$P1 < P2 < P3 < P4 < P5.$$

These differences in height correspond to the positions, in the direction of extension of the axis X0, of the individual X-ray generation zones 27A, 27B, 27C, 27D, 27E of FIG. 6.

The state depicted in FIG. 6 is one in which the output rods 49 of the air cylinders 41a and 41b from FIG. 3 are extended to maximum length. At this time, the gap Q between the support plats 36b and the casing 25 is in a state of maximum opening. As shown in FIG. 8, the gap Q at this time is in a state such that even when the tallest stop member 73e has been inserted between the casing 25 and the support plate 36b, a gap is present between a distal end of the stop member 73e and the surface of the casing 25, while at the same time, a gap is present between the other distal end of the stop member 73a and the surface of the support plate 36b. With the gap Q between the support plate 36b and the casing 25 in a state of maximum opening in this way, when the rotating plate 86 has rotated as shown by arrow L in FIG. 6, any one of the stop members 73a, 73b, 73c, 73d, 73e will be able to enter the region R sandwiched by the casing 25 and the support plate 36b, and to do so without contacting the casing 25, i.e., without touching it.

Because the X-ray generator 2 of the present embodiment is configured in the above manner, in the event that, for example, the X-ray generation zone 27E in FIG. 6 is selected, first, the motor 69 is operated with the gap Q in a state of maximum opening, the output shaft 71 is rotated, and the stop member 73e is arranged at the center of the region R. At this time, the other stop members are arranged outside of the region R. In FIG. 3, the output rods 49 of the air cylinders 41a and 41b undergo contracting motion. The support plate 36b thereby undergoes parallel, motion towards the casing 25 as shown by arrow J. At this time, in FIG. 8, the distal end (the distal end at the lower side in FIG. 8) of the head portion of the stop member 73e first comes into abutment against the casing 25, and is then further pressed.

Next, the compression spring 75 is compressed, and finally the distal end at the opposite side of the stop member 73e (the distal end at the top side in FIG. 9) abuts the surface of the support plate 36b as shown in FIG. 9, and parallel motion of the support plate 36b in the direction of arrow J halts. In this way, the stop member 73e functions as an accurate positioning stopper for halting the motion of the support plate 36b.

There is no limitation to selecting the stop member 73e which corresponds to the X-ray generation zone 27E, and through appropriate selection of the stop member 73a-73e corresponding to the desired X-ray generation zone 27A-27E, the desired X-ray generation zone can be arranged correctly and accurately at the prescribed position. Moreover, by designing the stop members 73a-73e to be slideable with respect to the rotating plate 68, the rotating plate 68 and the output shaft 71 are not subjected to an axial load, a radial load, or a moment load, and positioning of the anode 17 among a multitude of positions can be accomplished with the compressive load of the stop members 73a-73e only.

Where the one X-ray generation zone 27E is facing the cathode 16 in FIG. 4 in the manner described above, when electrons are emitted from the cathode 16, the electrons collide with the X-ray generation zone 27E, and X-rays of

14

wavelength corresponding to the metal of which the X-ray generation zone 27E is formed are emitted in all directions from, the X-ray generation cone 27E. Some of the X-rays are then extracted to the outside through the X-ray window 28.

As stated above, these X-rays R1 are utilized for X-ray analysis measurements in FIG. 1.

When it has become necessary to produce X-rays from an X-ray generation zone other than the X-ray generation zone 27E in order to change the conditions of X-ray analysis measurement, first, the air cylinder 41a and the air cylinder 41b are simultaneously made to undergo extending motion in FIG. 3, and the anode support body 32 (i.e., the support plate 36b) is retracted to a position furthest away from the casing 25. In so doing, the system is set to a state in which the gap Q between the support plate 36b and the casing 25 is at maximum opening, as shown in FIG. 6 and FIG. 8. In so doing, a state in which the rotating plate 68 which supports the stop members 73a, 73b, 73c, 73d, 73e can rotate freely between the support plate 36b and the casing 25.

Next, the rotating plate 68 is rotated by the motor 69 in such a way that, from among the stop members 73a-73d of FIG. 8, a stop member (any one of 73a, 73b, 73c, and 73d) of height corresponding to a desired X-ray generation zone, 25 which X-ray generation zone is different from the X-ray generation zone 27E of FIG. 3, is positioned at the center of the region R between the casing 25 and the support plate 36b. Subsequently, the air cylinders 41a, 41b of FIG. 3 are operated, and the output shafts 49 are made to undergo contracting motion until halted by the stop member. By means of this contracting motion, the X-ray generation zone (any one of 27A, 27B, 27C, and 27D) that corresponds to the height of the stop member (any one of 73a, 73b, 73c, and 73d) that is present within the region R of FIG. 6 can be arranged in a secure state at a position facing the cathode 26.

When thermal electrons are emitted from the cathode 16 in this state, X-rays of wavelength corresponding to the metal of which the facing X-ray generation zone (any one of 27A, 27B, 27C, and 27D) is formed are emitted from that 40 X-ray generation zone, and a portion thereof are extracted to the outside from the X-ray window 28 of FIG. 4.

As shown in FIG. 2, in the present embodiment, all of the elements among the air cylinders 41a, 41b serving as the driving means, the linear guides 42a, 42b serving as the guide means, the assist units 43a-43c serving as the elastic force-imparting means, and the stopper devices 44a-44d serving as the stopper means are provided together on the support plate 36b which is a single member, and specifically on the second flange 36b of the bellows 36, whereby the X-ray generator 2 can be given an overall configuration which is very compact.

In FIG. 2, the surface 36c of the support plate 36b which is the second flange of the bellows 36 is orthogonal to the center axis X1 of the bellows 36. The two air cylinders 41a and 41b are provided at different positions within this surface 36c. Further, the air cylinders 41a and 41b are provided at uniformity with respect to the center axis X1 of the bellows 36. Further, the two linear guides 42a and 42b are also provided at different positions within the surface 36c. The linear guides 42a and 42b are also provided at uniformity with respect to the center axis X1 of the bellows 36.

Further, the four assist units 43a-43d are also provided at different positions within the surface 36c. The assist units 43a-43d are also provided at uniformity with respect to the center axis X1 of the bellows 36. Further, the four stopper devices 44a-44d are provided at different positions within

this surface 36c. The stopper devices 44a-44d are provided at uniformity with respect to the center axis X1 of the bellows 36.

In the present description, "uniformity" of the plurality of members refers to a state of arrangement of the plurality of members in such, a way that when equal forces are applied to the members in the same direction, the point of application of the resultant force which is a force synthesized from, these forces is generally aligned with the center axis X1 of the bellows 36 serving as the seal member. Here, the term "generally" in the wording "generally aligned" is used in a sense that includes cases in which the point of application of the resultant force diverges from the center axis X1 by an extent such that the anode unit 24 supported by the anode support body 32 as shown in FIG. 3 and FIG. 4 can undergo parallel motion without significant tilt and with no practical difficulty.

Specifically, in FIG. 2, when forces of equal magnitude are applied, in the same direction to the two air cylinders 41a and 41b, the point of application of the resultant force thereof is generally aligned with the center axis X1 of the bellows 36. More specifically, the air cylinder 41a and the air cylinder 41b have a point-symmetrical positional relationship in relation to the center axis X1 of the bellows 36. Also, within the surface 36c of the second flange 36b, the air cylinder 41a and the air cylinder 41b have a line-symmetrical relationship in relation to a line C-C passing through the center axis X1 of the bellows 36. Moreover, the air cylinder 41a and the air cylinder 41b are arranged equidistantly from the center axis X1 of the bellows 36, and at equal intervals of 180°.

Additionally, when forces of equal magnitude are applied in the same direction to the two linear guides 42a and 42b, the point of application of the resultant force thereof is generally aligned with the center axis X1 of the bellows 36. More specifically, the linear guide 42a and the linear guide 42b have a point-symmetrical positional relationship in relation to the center axis X1 of the bellows 36. Also, within the surface 36c of the second flange 36b, the linear guide 42a and the linear guide 42b have a line-symmetrical relationship in relation to a line B-B passing through the center axis X1 of the bellows 36. Moreover, the linear guide 42a and the linear guide 42b are arranged equidistantly from the center axis X1 of the bellows 36, and at equal intervals of 180°.

The four assist units 43a-43d are arranged at the four corners of a hypothetical oblong L centered on the center axis X1. Therefore, when forces of equal magnitude are applied in the same direction to the assist units 43a-43d, the point of application of the resultant force thereof is generally aligned with the center axis X1 of the bellows 36. More specifically, the assist units 43a-43d have a point-symmetrical positional relationship in reaction to the center axis X1 of the bellows 36. Also, within the surface 36c of the second flange 36b, the assist units 43a-43d have a line-symmetrical relationship in relation to the line B-B and the line C-C, respectively, which pass through the center axis X1 of the bellows 36.

Further, when forces of equal magnitude are applied in the same direction to the four stopper devices 44a-44d, the point of application of the resultant force thereof is generally aligned with the center axis X1 of the bellows 36. More specifically, the stopper devices 44a-44d have a point-symmetrical positional relationship in relation to the center axis X1 of the bellows 36. Also, within the surface 36c of the second flange 36b, the stopper devices 44a-44d have a line-symmetrical relationship in relation to the line B-B and the line C-C, respectively, which pass through the center axis

X1 of the bellows 36. The stopper devices 44a-44d are arranged equidistantly from the center axis X1 of the bellows 36, and at equal intervals of 180°.

As shown above, in the present embodiment, the plurality 5 of air cylinders 41a, 41b, the plurality of linear guides 42a, 42b, the plurality of assist units 43a-43d, and the plurality of stopper devices 44a-44d are respectively arranged with uniformity in relation to the center axis X1 of the bellows 36, and therefore when the anode unit 24, driven by the air cylinders 41a, 41b, undergoes advancing and retracting motion with respect to the casing 25, the anode 17 experiences proper parallel motion with no lateral swaying or tilting. Consequently, the five X-ray generation zones 27A-27E in FIG. 4 can face the cathode 16 at the same distance and the same angle with respect to the cathode 16. That is, correct, reproducible positional accuracy of the X-ray generation zones 27A-27E with respect to the cathode 16 can be obtained.

In the present embodiment, the stop members 73a-73e of 20 FIG. 6, driven by the motor 69, change the positions of the X-ray generation zones 27A-27E of the anode 17, and therefore position adjustment of the X-ray generation zones 27A-27E can be accomplished automatically instead of manually. Further, conventionally, the distal end surface of 25 a check bolt was employed as a stopper to adjust the positions of three or more X-ray generation zones, and the amount of threading of the check bolt was varied in order to change the position of the distal end surface of the check bolt. With this method, the positions of the X-ray generation zones could not be finely adjusted with high accuracy 30 automatically.

By contrast, in the present embodiment, any one of the 35 plurality of stop members 73a-73e of different heights can be selectively interposed between the anode support body 32 and the casing 25, so as to adjust the relative positions of the anode 17 supported by the anode support body 32 and the cathode 16 supported by the casing 25, whereby the relative 40 positions of the cathode 16 and the X-ray generation zones 27A-27E an the anode 17 can be adjusted with high accuracy.

(Other Embodiments)

While the present invention has been described above in terms of its presently preferred embodiment, the present invention is not limited to this embodiment, and various modifications are possible within the scope of the invention disclosed in the claims.

For example, in the aforescribed embodiment, the rotating 45 plate 68 was employed as the mobile platform as shown in FIG. 6. However, a platform designed to undergo direct 50 advance motion may be employed to configure the mobile platform. The means for driving the mobile platform is not limited to a motor designed for rotary driving of a target object, and a drive device designed for direct advance driving of a target could be selected.

When working the present invention, it is not always 55 necessary to employ guide means like the linear guides 42a, 42b shown in FIG. 4, or elastic force-imparting means like the assist units 43a, 43b, 43c, 43d shown in FIG. 5.

FIG. 10 shows yet another embodiment. In this embodiment, a single X-ray generation zone 27E is formed from 60 two types of metals, a first metal 33a and a second metal 33b. These metals 33a and 33b are arranged alternately in the circumferential direction of the rotating anode 17. The first metal 33a is copper (Cu) for example, and the second metal 33b is molybdenum (Mo), for example.

The reason for forming a single X-ray generation zone 65 from a plurality of different types of metals is so as to be able

to generate X-rays of different wavelengths (i.e. different energies) from a single X-ray generation zone. Such an X-ray generation structure is disclosed by way of a striped target, for example, in Japanese latent Publication No. 5437180.

In the present embodiment, it is acceptable to employ three or more types of metals to form a single X-ray generation zone.

The invention claimed is:

1. An X-ray generator, comprising:
a cathode for generating electrons;
an anode provided facing the cathode, and equipped with
a plurality of X-ray generation zones which are lined up
adjacently to one another;
a casing for housing the cathode and the anode in the
interior thereof, and integrated with the cathode;
an anode support body for supporting the anode;
driving means for driving the anode support body in such
a way that the anode support body and the casing
undergo relative advancing and retreating movement;
and
stopper means for stopping motion of the anode support
body when the anode support body and the casing
move in a direction of approaching one another;
the stopper means comprising:
a mobile platform equipped with a section that enters and
exits from between the anode support body and the
casing,
a mobile platform drive means for driving the mobile
platform, and

a plurality of stop members of mutually different heights
provided in the entering and exiting section of the
mobile platform.

2. The X-ray generator according to claim 1, wherein the
mobile platform is provided in such a way as to be able to
move in a direction closer towards or away from the casing,
in a state in which at least one of the plurality of stop
members is placed between the anode support body and the
casing.

3. The X-ray generator according to claim 2, wherein the
stop member is urged by elastic member.

4. The X-ray generator according to claim 2, wherein the
stop members have lengths that are greater than the thick-
ness of the mobile platform,

the stop members are provided to pass through the mobile
platform, and

the stop members are configured such that one end thereof
is capable of abutting against either the casing or the
anode support body, and the other end of the stop
member is capable of abutting against the other of the
casing or the anode support body.

5. The X-ray generator according to claim 1, wherein the
mobile platform is a rotating plate,

the entering and exiting sections are peripheral sections of
the rotating plate, and

the plurality of stop members are provided at different
positions of the peripheral sections of the rotating plate.

6. The X-ray generator according to claim 5, wherein the
mobile platform moving means is a motor,

the motor has a main body section, and an output shaft
that extends to the outside from the interior of the main
body section,

the rotating plate is attached to the output shaft, and
the main body section of the motor is secured to the anode
support body or to the casing.

7. The X-ray generator according to claim 1, wherein a
plurality of the stopper means are provided on the anode
support body or on the casing.

8. The X-ray generator according to claim 7, further
comprising a seal member for airtightly partitioning a space
between the anode support body and the casing, wherein

the plurality of stopper means being arranged point-
symmetrically with respect to the center axis of the seal
member within a plane orthogonal to the center axis, or
line-symmetrically with respect to a line that passes
through the center axis.

9. The X-ray generator according to claim 8, wherein the
stopper means are arranged at mutually equidistant spacing
with respect to the center axis of the seal member, and at
mutually equiangular spacing about the center axis.

10. The X-ray generator according to claim 7, wherein the
seal member is a bellows, and

the stopper means are provided outside the bellows.

11. The X-ray generator according to claim 1, wherein the
anode support body comprises;

an anode housing that supports the anode and extends to
the outside of the anode, and
a support plate that is secured to the anode housing and
extends in a direction traversing the direction of exten-
sion of the anode housing,

the drive means and the stopper means are arranged on the
support plate.

12. An X-ray analyzer comprising:
the X-ray generator according to claim 1, and
an X-ray optical system employing X-rays generated by
the X-ray generator.
